US00D907465S

(12) **United States Design Patent** (10) **Patent No.:** **US D907,465 S**
Buse (45) **Date of Patent:** **** Jan. 12, 2021**

(54) **SERPENTINE RETAINER SPRING FOR A RECEPTACLE RACK**

(71) Applicant: **Gen-Probe Incorporated**, San Diego, CA (US)

(72) Inventor: **David Aaron Buse**, San Diego, CA (US)

(73) Assignee: **GEN-PROBE INCORPORATED**, San Diego, CA (US)

(**) Term: **15 Years**

(21) Appl. No.: **29/682,739**

(22) Filed: **Mar. 7, 2019**

(51) **LOC (13) Cl.** **08-05**

(52) **U.S. Cl.** **USPC D8/354**

(58) **Field of Classification Search**

USPC **D8/354**

CPC **F16F 1/02**

(57) **CLAIM**

The ornamental design for a serpentine retainer spring for a receptacle rack, as shown and described.

DESCRIPTION

FIG. 1 shows a top perspective view of the serpentine retainer spring for a receptacle rack.

FIG. 2 shows a side elevation view thereof.

FIG. 3 shows a right end elevation view thereof.

FIG. 4 shows a top plan view thereof; and,

FIG. 5 shows a bottom perspective view thereof.

The dash-dash broken lines in the drawings depict environmental structure and form no part of the claimed design. The dash-dot broken lines show the boundary of the claim and form no part of the claimed design.

1 Claim, 3 Drawing Sheets
